UNITED STATES PATENT OFFICE.

JOSIAH S. ROBBINS, OF ALLENTEWON, NEW JERSEY.

COMBINED CLOTHES WASHING, RINSING, AND DRYING MACHINE.

1,175,815.

Specification of Letters Patent. Patented Mar. 14, 1916.

Application filed November 1, 1915. Serial No. 59,089.

To all whom it may concern:

Be it known that I, JOSIAH S. ROBBINS, a citizen of the United States, residing at Allentown, in the county of Monmouth and State of New Jersey, have invented certain new and useful Improvements in Combined Clothes Washing, Rinsing, and Drying Machines; and I do declare the following to be a full, clear, and exact description of the invention, such as will enable others skilled in the art to which it appertains to make and use the same.

My invention relates broadly to improvements in washing machines, and has for its object to so improve upon the construction of such devices as to allow them to be used not only for washing the clothes, but for rinsing and drying the same.

To this end, the invention consists of certain novel features of construction and unique combinations of parts to be herein-after fully described and claimed, the descriptive matter being supplemented by the accompanying drawings which constitute a part of this application and in which,

Figure 1 is a side elevation of a washing machine constructed in accordance with my invention; Fig. 2 is a similar view taken at right angles to Fig. 1; Fig. 3 is a vertical section of the improved machine showing more particularly the driving means therefor; Fig. 4 is a vertical section taken at right angles to Fig. 3 and showing the relative positions of parts while washing; Fig. 5 is a similar view showing the application of such parts when drying the clothes; Fig. 6 is a detail vertical section through the foot lever and the ear thereon, this view being taken substantially upon the line 6-6 of Fig. 5; and Fig. 7 is a horizontal sectional view as seen on the plane of the line 7-7 of Fig. 3.

In specifically describing the invention, reference will be made to the drawings above briefly described by similar characters placed on corresponding parts throughout the several views.

To this end, the numeral 1 designates an appropriate tub here shown of common construction, being increased in height by the provision of an upstanding flange 2 of sheet metal or the like, to whose upper edge an appropriate cover 3 is hinged.

Having its lower end inserted through the bottom of the tub is an upright sleeve 4, such sleeve being preferably held in position

by nuts 5 threaded thereon in contact with the upper and lower sides of said bottom. The sleeve 4 rises to an appropriate height within the tub 1 and both rotatably and slidably receives an upright shaft 6, such shaft being preferably of rectangular design throughout its length and having its lower end received in a socket or the like 7 carried by the inner end of a horizontal foot lever 8, such lever being fulcrumed between its ends to a hanger 9 depending from the tub, while its outer end is equipped with an appropriate foot pedal 10. Said outer end of the lever 8 is also provided with a depending ear 11 having a series of vertically spaced openings 12 adapted to receive therein the bill 13 on the lower end of a hook shank 14 which is pivoted to and depends from the tub 1. It is to be understood that only the corners of the shaft 6 contact with the sleeve 4. Thus although the shaft in question is free to rotate and slide vertically, very little friction will exist between it and said sleeve.

The shaft 6 passes slidably through the hub of a horizontal bevel gear 15 supported by and meshing with an upright bevel gear 16 which is keyed to a horizontal shaft 17, the latter being rotatably mounted in appropriate bearings depending from the tub 1. One end of the shaft 17 is equipped with a comparatively small sprocket wheel 18 around which a sprocket chain 19 passes, such chain being driven by a relatively large sprocket wheel 20 equipped with an appropriate crank 21 if hand power is to be employed, or with a pulley wheel or the like if the machine is to be mechanically driven. Obviously, however, an electric motor might well be used for driving the wheel 20 at will.

Preferably, though not necessarily, the shaft 17 projects beyond the sprocket wheel 18 and is squared as shown at 22 for reception in a square opening in the end of an operating lever 23, whereby said lever may be attached and detached when desired.

Rotatably disposed within the tub 1 is an appropriate clothes basket 24 here shown as formed of wire netting properly reinforced, the bottom of said basket being equipped with an upstanding sleeve 25 loosely surrounding the sleeve 4 and having at its upper end a cap 26 formed with a central rectangular opening receiving the upper end of the square shaft 6, a set screw 27

being preferably threaded through said cap and into contact with the shaft to prevent relative vertical movement of the two. However, other means might well be provided for the attainment of this end.

Positioned loosely within the basket 25 and having a ribbed lower side, is a rubbing ring 28 preferably constructed of wood, said ring being equipped with a number of upwardly and outwardly curved arms 29 received slidably in upright channel shaped guides 30 secured to the inner side of the tub 1. Thus, the ring 28 may move vertically according to requirements, but may not rotate until raised to such an extent as to allow the arms 29 to disengage the guides 30.

When operating the machine, the cover 3 is opened, the basket 24 is filled with the clothes to be washed either before or after partially filling the tub with washing fluid, the rubbing ring 28 is applied to use in contact with the upper side of such clothes, and the cover 3 is closed. The handle 23 is now applied to the squared end 22 of the shaft 17 and such shaft is oscillated, thus oscillating the upright shaft 6 and in turn imparting such movement to the basket 24, it being of course understood that the latter is submerged in the fluid in the tub 1. This operation effectively washes the soiled clothes, it being obvious that the rubbing ring 28 plays an important part, since it may not rotate, whereas the clothes within the basket 35 are constantly moved to and fro over its ribbed under side.

When the clothes are to be rinsed, the foot pedal 10 is alternately depressed and released, thus rapidly reciprocating the basket 40 24 vertically through the fluid. The fluid previously used for washing must be drained out and a fresh supply used for rinsing purposes. While rinsing, the arms 29 will slide vertically in the channel-shaped guides 30 as will be obvious from an inspection of the drawings. The rinsing operation completed, 45 drying is next to be done. This is accomplished by depressing the foot pedal 10 to raise the basket 24 and its contents above the water level in the tub, whereupon the hook nose 13 is inserted in an appropriate opening 12 to prevent lowering of said basket. The handle 23 is now removed, and the crank 21 is actuated to swiftly rotate the basket 24, through the instrumentality of the driving connections above described. The result is that all moisture will be thrown outwardly from the clothes into the tub by centrifugal force, thereby rendering

the use of a wringer unnecessary. Raising 60 of the basket to a level for drying the clothes therein will dispose the arms 29 in a plane above the guides 30, thereby allowing the basket to be rotated without removing the rubbing ring 28. This salient feature 65 will be obvious from the drawings, even though in Fig. 5 the ring has been removed.

From the foregoing, it will be obvious that I have provided a single machine for washing, rinsing and drying the clothes 70 without once removing the same, this being deemed a marked advance in the class of devices to which my invention relates, since it undoubtedly reduces the cost and labor of washing to a minimum.

In the drawings, certain specific details of construction have been shown for illustrative purposes, and in the preceding such details have been described, but it is obvious that numerous changes may be made within 80 the scope of the invention as claimed without sacrificing any of the advantages thereof.

I claim:—

A combined clothes washing, rinsing and 85 drying machine comprising an upright cylindrical tub adapted to be partially filled with washing fluid, a pervious clothes basket mounted concentrically in said tub and having an open upper end, means for rotating 90 or oscillating said basket whereby to cleanse its contents when submerged in the washing fluid, and means for swiftly reciprocating said basket vertically through such fluid to rinse such contents, said last named 95 means also serving to hold said basket elevated above the fluid whereby when swiftly rotated its contents will be dried by centrifugal force, a clothes rubber inserted in the open upper end of the basket, an arm radiating from said rubber above the upper edge of the basket, and an upright guide secured to the wall of the tub and engaged by said arm to hold the rubber against rotation when washing and rinsing, the arm being 100 allowed to slide in respect to the guide when performing the last named operation, said guide being of a length to be disengaged by said arm when the basket is raised for 105 drying.

In testimony whereof I have hereunto set my hand in presence of two subscribing witnesses.

JOSIAH S. ROBBINS.
